UNITED STATES PATENT OFFICE

163,229

REAR-VISION MIRROR

Porter E. Stone, Detroit, Mich.

Application August 31, 1949, Serial No. 4,776

Term of patent 14 years

(Cl. D14—6)

To all whom it may concern:

Be it known that I, Porter E. Stone, a citizen of the United States of America, residing at Detroit, in the county of Wayne and State of Michigan, have invented a new, original, and ornamental Design for a Rear-Vision Mirror, of which the following is a specification, reference being made to the accompanying drawing, forming part thereof.

Fig. 1 is a front elevation showing my rear-vision mirror.

Fig. 2 is an end elevation,

Fig. 3 is a rear elevation, and

Fig. 4 is a side elevation of the same.

I claim:

The ornamental design for a rear-vision mirror, substantially as shown.

PORTER E. STONE.
